UNITED STATES PATENT OFFICE.

JOSEPH F. BRIGHTMAN, OF SYRACUSE, NEW YORK, ASSIGNOR TO THE SYRACUSE FAUCET AND VALVE COMPANY, OF SYRACUSE, NEW YORK, A CORPORATION OF NEW YORK.

DESIGN FOR A RADIATOR-VALVE CASING AND HANDLE.

53,405.

Specification for Design.

Patented June 10, 1919.

Application filed February 7, 1916. Serial No. 76,865. Term of patent 3½ years.

To all whom it may concern:

Be it known that I, JOSEPH F. BRIGHTMAN, a citizen of the United States, residing at Syracuse, in the county of Onondaga and State of New York, have invented a new, original, and ornamental Design for a Radiator-Valve Casing and Handle, of which the following is a specification, reference being had to the accompanying drawing, forming a part hereof.

The drawing is a perspective view looking downwardly on my radiator valve casing and handle.

This design for a valve casing and handle includes a lengthwise peripheral surface 1 on the body of the valve casing which surface bulges at 2 at its middle and curves at 3 inwardly at its upper and lower ends and then slightly outwardly at 4, the peripheral surface 1 terminating at its upper end in the cylindrical band 5, and at its lower end in a hexagonal band 6. The design further includes a surface 7 on an intermediate or waist portion located above the body, this surface 7 flaring outwardly in comparatively

long easy curves at 8 at its lower end which meet the upper edge of an octagonal surface 9 located above the peripheral cylindrical band 5, and said surface 7 terminating at its upper end in a raised cylindrical band 10.

This design also includes surfaces 11 on the upper portion of the valve casing which are similar to the surface 7 on the intermediate portion but of less diameter and height or length than the same, and a peripheral surface 12 on the hub of the handle wheel 13 above the upper portion, this surface 12 flaring outwardly at its upper end and being coincident at its lower end with the raised peripheral surface 14.

I claim:

The ornamental design for a radiator valve casing and handle, substantially as shown and described.

In testimony whereof, I have hereunto signed my name at Syracuse, in the county of Onondaga, and State of New York, this 23rd day of October, 1915.

JOSEPH F. BRIGHTMAN.
